(57) **CLAIM**

The ornamental design for a hearing aid component as shown and described.

DESCRIPTION

FIG. 1 is a perspective view of a hearing aid component according to a first embodiment;

FIG. 2 is a back view thereof;

FIG. 3 is a front view thereof;

FIG. 4 is a left view thereof;

FIG. 5 is a top view thereof;

FIG. 6 is a bottom view thereof;

FIG. 7 is a right thereof;

FIG. 8 is a perspective view of the hearing aid component according to a second embodiment;

FIG. 9 is another perspective view thereof;

FIG. 10 is a back view thereof;

FIG. 11 is a front view thereof;

FIG. 12 is a left view thereof;

FIG. 13 is a top view thereof;

FIG. 14 is a bottom view thereof;

FIG. 15 is a right view thereof;

FIG. 16 is a perspective view of a hearing aid component according to a third embodiment;

FIG. 17 is a back view thereof;

FIG. 18 is a front view thereof;

FIG. 19 is a left view thereof;

FIG. 20 is a top view thereof;

FIG. 21 is a bottom view thereof; and,

FIG. 22 is a right view thereof.
